CLAIM

The ornamental design for a dual-dispensing container, as shown and described.

DESCRIPTION

FIG. 1 is a front elevational view of the dual dispensing container showing our new design;

FIG. 2 is a left side elevational view thereof;

FIG. 3 is a right side elevational view thereof;

FIG. 4 is a top plan view thereof;

FIG. 5 is a bottom plan view thereof;

FIG. 6 is a top front perspective view thereof; and,

FIG. 7 is a bottom front and side perspective view thereof.
